DIVIDERS AND ADJUSTABLE POINT THEREFOR

Filed March 12, 1929

FIG. 1.

FIG. 2.

FIG. 3.

FIG. 4.

Inventor:

August Renzelberg

UNITED STATES PATENT OFFICE

AUGUST RENZELBERG, OF NUEREMBERG, GERMANY

DIVIDERS AND ADJUSTABLE POINT THEREFOR

Application filed March 12, 1929, Serial No. 346,408, and in Germany May 4, 1928.

This invention relates to dividers and more particularly to dividers comprising an adjustable point for one of the legs thereof. In a known construction of this kind there is 5 provided a fixed center of rotation on the leg of the divider, said fixed center of rotation serving as an axle around which the adjustable point may be swung, while the point is provided with a resilient extension and a 10 pressure screw below said extension.

The dividers according to my present invention, in contra-distinction to known constructions, comprise a point in the form of a shank which at its rear end is provided 15 with a stop, support or the like engaging with an abutment located within a groove in the leg of the dividers. According to my invention, furthermore, said rear end of the shank is of bow-shaped conformation and 20 is engaged at a place about at its center by the head of a threaded spindle.

By my invention on the one hand the advantage is secured that the manufacture of the adjustable point for the dividers will be 25 greatly simplified on account of the fact that a fixed center of rotation which ordinarily serves for the adjustment of the point will be dispensed with. In addition to this, there will be the advantage that the adjusting 30 screw for the point of the dividers will solely be exposed to tensional strains, this resulting in the possibility of attaining a finer adjustment that had heretofore been possible when employing an adjusting device in the form 35 of a pressure screw as had been usual in connection with adjustable points for dividers.

According to my invention the adjustable point of the dividers is fixed upon the respective leg of the dividers solely by inserting 40 said point into said leg and by providing a stop or abutment adapted to properly support the adjustable point at or near its rear end within said leg. By so constructing the 45 adjustable point of the dividers, said adjustable point may easily be mounted within and removed from said dividers without it being necessary to send the latter to the factory for repair.

The accompanying drawings represent an 50 embodiment of my invention, Fig. 1 being a

view of the dividers and of the exchangeable and adjustable point constructed according to my invention, said view showing said dividers in spread condition together with the leg which is provided with the adjustable point partly in cross-section, Fig. 2 a partial view of said leg taken from the inside of the spreaded dividers, Fig. 3 a partial cross-section through the leg of the dividers shown in Fig. 2, and Fig. 4 a separate view of the 60 adjustable and exchangeable point shown in Figs. 1 and 2.

Referring now more particularly to the drawings, the leg 1 of the dividers is adapted to receive a shank in the form of an adjustable and exchangeable point by means of a groove 2 which is milled into said leg 1 in longitudinal direction thereof. A stop or abutment 3 in the form of a pin or the like passes 65 transversely through said groove 2. The upper part of the adjusting point consists of a resilient curved extension 6 which at its free end is provided with a recess 7 abutting against said pin 3, while the lower part of 70 said adjustable point projects longitudinally from said leg and forms the point proper thereof. More particularly, the resilient curved extension 6 in normal condition is bent towards the inside of the dividers, while 75 the back 9 of said resilient bow-shaped extension 6 is flat permitting proper resiliency thereof. Intermediate the extension 6 and the member 5 which is of cylindrical cross-section there is provided a threaded spindle 80 as shown, for instance, in Fig. 4 of the drawings. In order to fix the threaded spindle at a proper place within the leg 1 of the dividers and in order to prevent the resilient curved extension 6 of the adjustable point 85 against slipping out in the groove 2 of said leg 1, there is provided near the seat for the adjusting nut on the threaded spindle a small recess which constitutes an upper and under stop for the head of the threaded spindle, as 90 may be seen from Fig. 1.

The adjustable and exchangeable point of the dividers which is composed of the point proper 4 and the resilient curved rear extension 6 is inserted into the groove 2 of the leg 1 95 of the dividers in such a manner that the re- 100

- cess 7 provided at the rear end of said extension 6 will engage with the pin or abutment 3, while the threaded spindle which serves for the adjustment of said point 4 passes to-
5 wards the outside through a bore at the bottom of said groove. The adjusting nut as indicated in the drawings is threaded upon said spindle and engages with the outer surface of the leg 1 of the dividers.
- 10 Upon actuating the adjusting device by drawing tight the adjusting screw, the resil-
ient extension 6 by reason of its bow-shaped conformation and its resiliency now will cause the point 4 to move in inward direction
15 of the dividers. In this manner the point 4 may follow the motion of said adjusting nut, thus securing the desired fine adjustment with respect to the fixed point of the other leg of the dividers.
- 20 In general, therefore, my invention pro-
vides an adjustable point for dividers, said point being fixed on one of the legs thereof solely by insertion thereinto in longitudinal direction, while an abutment or stop serves
25 as a proper rear support for said point which may be adjusted by a nut with respect to the fixed point of the other leg of the dividers. In addition to this, the adjustable point accord-
ing to my present invention may easily
30 be mounted upon and removed from the res-
pective leg of the dividers and readily ex-
changed if required.

I claim:

1. In dividers, the combination of a pair
35 of legs, there being a groove provided lon-
gitudinally in one of said legs adjacent its end, an adjustable point having a rearward curved resilient extension adapted to be in-
40 serted into said groove, there being a recess
at or near the free end of said resilient curved extension, an abutment in said groove adapted to engage in said recess, and an adjusting de-
vice permitting to change the curvature of
45 said extension, thus to adjust said point with
respect to said one leg, said adjusting device comprising a threaded spindle having a head
engaging said resilient extension and an ad-
justing nut engaging said leg.

2. Dividers as specified by claim 1, in
50 which the adjusting nut is adapted to move
said point away from the point of the other
leg when drawing tight said adjusting nut.

In testimony whereof I affix my signature.

AUGUST RENZELBERG.
